DESIGN FOR A HANDLE FOR SADIRON

George T. Scharfenberg, Chicago, Ill., assignor to Chicago Flexible Shaft Company, Chicago, Ill., a corporation of Illinois

Application September 12, 1938, Serial No. 79,839

Term of patent 7 years

To all whom it may concern:

Be it known that I, George T. Scharfenberg, a citizen of the United States, residing at Chicago, in the county of Cook and State of Illinois, have invented a new, original, and ornamental Design for a Handle for Sadiron, of which the following is a specification, reference being had to the accompanying drawing, forming part thereof.

In the drawing:

Figs. 1 and 2 are side perspective views of a handle for sadiron showing my new design, and Fig. 3 is a top view of the same.

I claim:

The ornamental design for a handle for sadiron, substantially as shown.

GEORGE T. SCHARFENBERG.
